M. A. POSSONS,
BURNER ATTACHMENT FOR GAS RANGES,
APPLICATION FILED JAN. 7, 1914.

1,186,228.

Patented June 6, 1916.

UNITED STATES PATENT OFFICE.

MINARD A. POSSONS, OF CLEVELAND, OHIO, ASSIGNOR TO AMERICAN STOVE COMPANY,
OF ST. LOUIS, MISSOURI, A CORPORATION OF NEW JERSEY.

BURNER ATTACHMENT FOR GAS-RANGES.

1,186,228.

Specification of Letters Patent.

Patented June 6, 1916.

Application filed January 7, 1914. Serial No. 810,896.

To all whom it may concern:

Be it known that I, MINARD A. POSSONS, a citizen of the United States, residing at Cleveland, in the county of Cuyahoga and State of Ohio, have invented certain new and useful Improvements in Burner Attachments for Gas-Ranges, of which the following is a specification, reference being had therein to the accompanying drawing.

10 My invention relates to improvements in burner attachments for gas ranges.

The object of my invention is to provide a gas range of this character in which the oven burners and broiler burner valves are 15 so connected that one cannot be turned on when the other is burning and vice versa, whereby it is impossible to cause an explosion by filling the oven with gas from one burner and igniting it by the other lighted 20 burner.

Another object of my invention is to provide a simple, cheap and effective attachment to accomplish the above result which 25 can be readily applied to the ordinary gas range now in use.

In the accompanying drawing—Figure 1 is a perspective view of one corner of a gas range showing my attachment applied thereto. Fig. 2 is an enlarged side elevation 30 of my improved attachment. Fig. 3 is an edge view of Fig. 2. Fig. 4 is an enlarged view of the lower end of the attachment showing the position of the connection rod in respect to the lower burner-valve when 35 the upper valve is open.

Referring now to the drawings, 1 represents a gas range, the oven 2 of which is provided at its upper and lower ends with burners provided with valves 3 and 4, for 40 supplying gas thereto. Heretofore these valves 3 and 4 have been independently operated and in such event when either of the burners is in operation and the other burner is turned on, the oven fills with gas and is 45 ignited often causing a serious explosion. By my improved attachment such an explosion cannot take place as it is impossible to turn on one of the burners when the other burner is in operation.

50 The valves 3 and 4, as heretofore described, control the gas to the upper and lower burners, one being the baking burner and the other the broiler, and are of the usual structure having the valve stems 5 and 6 operated by the handles 6' and 7',

and which needs no further description, as the specific form of valve forms no part of my invention. The valves 3 and 4 are arranged one directly above the other and the valve stem 5 of the upper valve is provided with two outwardly extending ears 7 and 8, between which is pivoted by the cotter pin 9, a rod 10 which extends downwardly. The lower end of said rod is provided with an enlarged flat portion 11, which extends 60 transverse the valve stem 6 and is provided with an inverted keyhole slot 11', through which the valve stem 6 passes and which I will now proceed to describe. The valve stem 6 is provided with an elongated member 12, which is of a width to snugly fit within the elongated portion 13, of the keyhole-slot and of such a length that it can turn within the round lower end 14 of the keyhole slot, as shown in Fig. 2. The valve 65 stem on each side of the elongated rectangular-shaped member is provided with obliquely arranged ears 15 and 16, which are adapted to extend out beyond the keyhole slot 11' and form a guide and support for 70 the lower flat end 11 of the rod 10, whereby the rod is supported. This arrangement of the ears prevents the necessity of any additional support for the rod. The valves 3 and 4 in Fig. 1, are both shown closed and 75 either can be operated by the handle to open the same for supplying gas to the upper or lower burner. The opening of the lower valve 4 causes the rectangular-shaped member 12 to turn in a horizontal position in 80 the round opening 14 of the keyhole-slot and thus the upper valve 3 being connected to the rod 10, cannot be opened as the member 12 prevents the downward movement of the rod, thus it is impossible to turn on the 85 upper burner when the lower burner is in operation. The turning off of the lower burner brings the member 12 in a vertical position and the upper valve can be operated, which forces the rod 10 down so that 90 the member 12 is within the slot 13. When the member 12 is within the slot 13, it will 95 be seen that the lower valve stem 6 cannot be turned and thus the lower burner cannot 100 be supplied with gas.

While I have shown and described this specific form of accomplishing these results, it is understood that the structure could be readily varied without departing from my invention.

105

110

Having thus described my invention, what I claim and desire to secure by Letters Patent is:

1. The combination with a gas range having upper and lower burners, valves for said burners having projecting valve stems, a rod having one end connected eccentrically to one valve stem, the other end of the rod having a key-hole shaped opening embracing the other valve stem, the last mentioned valve stem having a flat portion adapted to enter the narrow portion of the key-hole opening and locked against turning, whereby the two valve stems are alternately locked so that both valves cannot be open at the same time for the purpose described.
2. The combination with a gas range having an upper and a lower burner, a valve for each burner, an arm carried by the valve stem of one valve, a rod pivotally connected to said arm, an elongated member carried by the valve stem of the other valve and the lower end of the rod having an enlarged portion provided with a key-hole slot adapted to receive the transverse member carried by the valve stem whereby both valves cannot be opened at the same time.
3. The combination with a gas range having an upper and a lower burner, a valve for each burner, the valve stem of one burner having an outwardly extending arm, a rod pivoted to the said arm, the valve stem of

the other burner having a transverse elongated member, ears carried by the valve stem on each side of said member, the lower end of the rod having an enlarged flat portion provided with a key-hole slot to receive the transverse member to fit between the ears of the valve stem, whereby the rod is supported by the valve stem and both valves cannot be opened at the same time.

4. The combination with a gas range having an upper and a lower burner, a valve for each burner, the stem of one valve having two outwardly extending arms, a rod pivoted between said arms, the valve-stem of the other valve having a transverse elongated member, ears carried by the stem on each side of the said transverse member and arranged at an angle to said member, and the lower end of the rod having an enlarged flat portion fitting between the ears of the valve stem and having a key-hole slot adapted to receive the elongated transverse member whereby both valves cannot be opened at the same time, substantially as shown and described.

In testimony whereof I hereunto affix my signature in the presence of two witnesses.

MINARD A. POSSONS.

Witnesses:

E. A. SCHNEIDER,
F. T. BATCHELOR.
